DESIGN FOR A POWER DRIVEN PIPE STAND

William M. Emery, Cleveland Heights, and Arthur S. Gould, Lakewood, Ohio, assignors to The Oster Manufacturing Company, Cleveland, Ohio, a corporation of Ohio

Application October 7, 1938, Serial No. 80,312

Term of patent 7 years

To all whom it may concern:

Be it known that we, William M. Emery and Arthur S. Gould, citizens of the United States and residents of Cleveland Heights, county of Cuyahoga, and State of Ohio, and Lakewood, county of Cuyahoga, and State of Ohio, respectively, have invented a new, original, and ornamental Design for Power Driven Pipe Stand, of which the following is a specification, reference being had to the accompanying drawing, forming a part thereof.

In the accompanying drawing:

Fig. 1 is a front elevational view of a power driven pipe stand showing my new design;

Fig. 2 is a side elevation of the same taken from the left; and

Fig. 3 is a rear elevation of the same.

What we claim is:

The ornamental design for a power driven pipe stand, as shown.

WILLIAM M. EMERY.

ARTHUR S. GOULD.
